Inventor
John Robinson

United States Patent Office.

JOHN ROBINSON, OF PLAINFIELD, ASSIGNOR TO AARON SNELL
AND ARTHUR T. D. AUSTIN, OF WILL COUNTY, ILLINOIS.

Letters Patent No. 91,566, dated June 22, 1869.

IMPROVEMENT IN SULKY-CULTIVATORS.

The Schedule referred to in these Letters Patent and making part of the same.

Be it known that I, JOHN ROBINSON, of Plainfield, Will county, and State of Illinois, have invented a new and useful Improvement on a Sulky-Cultivator; and I do hereby declare the following to be a full, clear, and exact description of the same, reference being had to the annexed drawings, making a part of this specification, in which—

Figure 1 is a plan view,

Figure 2, a side elevation,

Figure 3, a rear elevation, and

Figure 4, a perspective view of the mode of attachment of the shovel-post to the beam.

My invention consists in an improvement on a sulky-cultivator, by means of which it is made easy to guide the shovels, and raise or lower the rear ends of the plow-beams to any desired point by the operator as he rides.

Also I claim to have improved the mode of attaching the shovel-posts to the beams, to throw the dirt to either side, by the device shown in fig. 4.

In order to enable others to understand my invention, I will proceed to explain the same.

a a are the plow-beams, attached by means of a swivel-joint to the post *c*, from the main frame *b*, the rear ends passing through and being held in place by the slotted upright posts *i i*.

These two slotted upright posts, *i i*, are attached together by means of the braces *o* and *p*, and slotted cross-bar *m*, and may be placed at any distance apart by means of the slot in the cross-bar *m*, fig. 1, and the row of holes in the brace *p*, fig. 3.

The upright posts *i i* pass up through between the rear end of the main frame *b* and the cross-bar *r*, and move horizontally by means of being suspended on the rollers *n n*, which roll from one side to the other on said frame, as shown.

The horizontal motion is imparted to the beams by

means of the operator placing his feet on the inner end of the levers *d d*, as he rides in the seat *e*.

It will be readily seen that by pressing down with the feet on the inner end of said levers, the outer end being under the beams *a*, will raise them up with but very little exertion, and it becomes a very easy matter to guide the shovels to either side desired.

Fig. 4 shows the means by which the two front shovel-posts are attached to the beams *a*.

s is a metal seat attached by bolt to the beam *a*, into which rests the post *v*.

The set-screw *u*, passing through the said metal seat into the post *v*, holds it in place.

By loosing the set-screw, the post may be turned so as to throw the shovel either to one side or the other, which is permitted by the swivel in the brace *t*.

The whole machine may be constructed of any suitable material, such as is ordinarily used in cultivators of this class, the whole being mounted on the wheels *x*, in the ordinary way.

The seat *e* may be moved either forward or backward, to accommodate the machine to the weight of the operator, so as to balance the machine and take the weight of the front end of the machine off the horses' neck.

Having thus described my invention,

What I claim as new, and desire to secure by Letters Patent, is—

1. The combination of the slotted metal seat *s*, post *v*, and swivel-brace *t*, with the shovel-beam *a*, arranged, operating, and constructed as and for the purposes set forth.

2. The general combination of all the parts described and shown, as and for the purposes set forth.

Witnesses:

JOHN ROBINSON,
THOS. H. HUTCHINS,
H. LOWE.
